DESIGN FOR A LIFTING HANDLE

Hoyt K. Foster, Hollis, N. Y., assignor to S. W. Farber, Inc., Brooklyn, N. Y., a corporation of New York

Application August 12, 1940, Serial No. 94,368

Term of patent 14 years

To all whom it may concern:

Be it known that I, Hoyt K. Foster, a citizen of the United States, residing at Hollis, in the county of Queens and State of New York, have invented a new, original, and ornamental Design for a Lifting Handle, of which the following is a specification, reference being had to the accompanying drawing, forming part thereof, wherein—

Fig. 2 is an end view,
Fig. 3 is a front elevation, and
Fig. 4 is a bottom view of the handle of Fig. 1;
Fig. 5 is a sectional view on the line 5—5 and
Fig. 6 is a sectional view on the line 6—6 respectively of Fig. 4.

I claim:
The ornamental design for a lifting handle, substantially as shown.

HOYT K. FOSTER.
